UNITED STATES PATENT OFFICE.

JULIA M. HOLLISTER, OF DES MOINES, IOWA.

DESIGN FOR AN ANIMAL TOY.

56,161.

Specification for Design. Patented Aug. 24, 1920.

Application filed April 27, 1920. Serial No. 377,124. Term of patent 7 years.

To all whom it may concern:

Be it known that I, JULIA M. HOLLISTER, a citizen of the United States, and a resident of Des Moines, in the county of Polk and State of Iowa, have invented a certain new, original, and ornamental Design for an Animal Toy, of which the following is a specification, reference being had to the accompanying drawing, forming part thereof.

Figure 1 is a front elevation; and
Fig. 2 shows a side elevation.

I claim:

The ornamental design for an animal toy,
as shown.

Des Moines, Iowa, April 5, 1920.

JULIA M. HOLLISTER.
